US0D1097335S

(12) **United States Design Patent** (10) **Patent No.:** **US D1,097,335 S**
(45) **Date of Patent:** **** Oct. 7, 2025**

(54) **PROTECTIVE GARMENT**

(71) Applicant: **DuPont Safety & Construction, Inc.**,
Wilmington, DE (US)

(72) Inventors: **Colin A. McLachlan**, Sumter, SC (US);
Judith Lee Denny-Lybbert, West
Columbia, SC (US); **Arthur Harrison**
Monk, Columbia, SC (US)

(73) Assignee: **DuPont Safety & Construction, Inc.**,
Wilmington, DE (US)

(**) Term: **15 Years**

(21) Appl. No.: **29/902,129**

(22) Filed: **Sep. 8, 2023**

(51) LOC (15) Cl. **02-02**

(52) U.S. Cl.

USPC **D29/100**

(57) **CLAIM**

The ornamental design for a protective garment, as shown and described.

DESCRIPTION

FIG. 1 is a top and front perspective view of a protective garment showing our new design;

FIG. 2 is a front view thereof;

FIG. 3 is a rear view thereof;

FIG. 4 is a right side view thereof;

FIG. 5 is a left side view thereof; and,

FIG. 6 is a top and rear perspective view thereof.

The dashed broken lines in the figures illustrate portions of the protective garment and environment that form no part of the claimed design.

1 Claim, 6 Drawing Sheets
